WIRING SYSTEM FOR ELECTRIC OVENS

Roscoe S. Heise, Wauseon, Ohio; Eyda Heise
executrix of said Roscoe S. Heise, deceasedApplication June 27, 1928, Serial No. 288,610
Renewed March 6, 1933

8 Claims. (CL 219—20)

This invention relates to a wiring system for electric ovens and the like of a type which can be readily connected or disconnected and transported from one place to another.

In ovens of this kind it is desirable that the heating units be of as large a size as may conveniently be the case so as to provide for rapid heating of the oven or plate. At the same time the regulations of the Fire Insurance Underwriters limit the amount of current which can be carried by various kinds of electrical equipment such as the flexible cord which it is desired shall be used to connect this electric oven to a standard electrical socket or other similar outlet.

An object of the invention, therefore, is to provide a wiring system for electric ovens of this type which enables a plurality of the electric heating units to be switched in on the line in various combinations but so limits the whole that no more than a predetermined maximum wattage can be exceeded by any possible setting of the switches.

Another object is to provide a set of switches which are so combined as to enable one of the heating units to be supplied at all times by an amount of wattage corresponding to the setting of its controlling switch, irrespective of the settings of the switches controlling the other heating units, while the other units shall receive an amount corresponding to the settings of their controlling switches so long only as the sum total of all power flowing through all said units of the oven does not exceed the predetermined total.

These and other objects, as will hereinafter appear, are accomplished by this invention which is fully described in the following specification and shown in the accompanying drawings, in which—

Figure 1 is a wiring diagram showing three heating units each controlled by a switch, the switch, however, being interconnected and all the switches being turned on full;

Fig. 2 is a similar diagram showing the central switch controlling the top oven heating element turned to a medium position;

Fig. 3 is a view similar to Fig. 2, but showing the central switch turned to a low position;

Fig. 4 is a similar view showing the central switch in an off position;

Fig. 5 is a view of the central controlled switch taken on line 5—5 of Fig. 7;

Fig. 6 is a view of the same on the line 6—6 of Fig. 7;

Fig. 7 is a horizontal longitudinal section of the central switch on the line 7—7 of Fig. 6;

Figs. 8 and 9 are longitudinal sections on the lines 8—8 and 9—9, respectively, of Fig. 6;

Fig. 10 is a perspective view of one of the rotatable contact members of the switch; and

Fig. 11 is a similar view of a companion contact member.

Referring now to the wiring diagram (Figs. 1 to 4), the top oven refractory element consists of two sections A¹ and A² which preferably lie upon the top and outside of the oven. The oven represented by the dotted line B has also a top oven refractory element consisting of two sections C¹ and C² and a bottom oven refractory element consisting of two sections D¹ and D². These heating elements, as will later be described, are controlled both individually and in combination by means of switches E, F, G, and H, the switches E and F being connected together so as to operate virtually as a single switch.

The switch E controls the top oven heating element A¹ and A², while the switches G and H control the top oven heating elements C¹ and C² and the bottom oven heating elements D¹ and D², respectively. The switches E, G and H are identical in construction and operation, and a description, therefore, of switch E will serve also as a description of switches G and H.

The switch E, shown in Figs. 5 to 11, has an insulating block of porcelain 10, or the like, which is secured, as will later be described, to a metallic bracket 11 by means of which it is mounted in an opening in the sheet metal housing (not shown) of the oven. The insulating block 10 is provided with a series of equally spaced posts E¹, E², E³, and E⁴ which have flanged bottoms E⁵ tapped to receive screws E⁶ which pass through the block 10. The post E¹ carries two spaced yieldable sheet metal fingers E⁷ which are adapted to spread apart so as to receive a lug E⁸ of a rotatable contact member E⁹ which is carried by a shaft E¹⁰ rotatably mounted in the center of the block 10. This shaft is rotated by means of a suitable handle E¹¹ which extends through an opening in the sheet metal cover E¹². This form of switch is well known to the trade under the name of "Diamond H" switch, and, therefore, need be described only in such detail as will show how it is used in the present circuit, particularly with the switch F which will later be described, and which combines with the switch E to form a system of control which is unique in the art.

The post E³ has fingers E¹³ which are adapted to engage the lugs E¹⁴ on the contact member E¹⁵ which is also carried by the shaft E¹⁰, the members E⁹ and E¹⁵ being insulated from each other. 110

Likewise the post E² (Fig. 9) carries contact fingers E¹⁶ and E¹⁷ which lie in the same planes as the contact fingers E⁷ and E¹³, respectively. Also the post E⁴ has a single contact finger E¹⁸ which is in the same plane as the fingers E¹³ and E¹⁷. The rotatable contact member E⁹ also has one other lug E¹⁹ which is spaced at 90 degrees from the lug E⁸. The rotatable contact member E¹⁵ has a lug E²⁰ which is spaced at 90 degrees from the lug E¹⁴. A lug 21 is placed opposite the lug E¹⁴.

The two contact members E⁹ and E¹⁵ are placed on the shaft in such a way that the lugs E¹⁴ and E⁸ are placed opposite to each other and the lug E²⁰ is placed opposite to the lug E¹⁹. The rotatable members are driven by means of a spring E²² (see Fig. 7), but this bracket mechanism will not be explained in detail as it is a part of the "Diamond H" switch which is well known in the art.

The switch F consists of a switch similar to the switch E and set back to back therewith after certain changes have been made therein as will now be described. The insulator block 12 is identical with the block 10 in the switch E, the two being set back to back and secured together by means of bolts 13. The shaft E¹⁰ is turned to rotate the shaft F¹⁰ substantially a corresponding amount. The shaft F¹⁰ has a rotatable contact member F⁹ corresponding to the member E⁹ of the switch E and a flat contact member F¹⁵ corresponding to the member E¹⁵ of the switch E.

The switch F has three posts F²², F²³, and F²⁴, which are disposed, as indicated, opposite the post E¹, E², and E³, respectively, of the switch E. The post F²² has two contact members F²⁵ and F²⁶ which align the planes of the lugs of the contact members F⁹ and F¹⁵, respectively. Likewise the post F²³ has two contact fingers F²⁷ and F²⁸, while the lug F²⁴ has a single contact finger F²⁹. There is no post on the switch F opposite the post E⁴ of the switch E. Corresponding numerals will be used to designate similar parts of the various switches, the only change being in the letters E, G and H with which they are used. Also such parts of the switch F, as correspond to similar parts of the switch E, are also given like numbers. The switch G has rotatable members G⁹ and G¹⁵ similar to the rotatable members E⁹ and E¹⁵ of the switch E.

Wiring of the circuit

A positive lead 16 is carried to the posts E³, G³, and H³ of the three switches E, G and H, respectively. The post E² of the switch E is carried through a lead 17 to one end of the heating section A² of the top oven heating element. This section of the heating element is connected to its companion section A¹ by means of a lead 18. The other end of section A¹ is then connected to the negative supply lead by means of a wire 19. This lead 19 connects through a wire 20 with the post E¹ of the switch E and through a wire 21 with the post F²⁴ of the switch F.

A lead 22 joins the lead 18 midway between the top oven sections A¹ and A² and connects it with the post E⁴ of the switch E. A lead 23 connects the post G⁴ of the switch G with a wire 24 connecting the top oven heater sections C¹ and C². The other end of the section C¹ connects through a lead 25 with the post F²² of the switch F and with the post H¹ of the switch H. The other end of the heater section C² connects through a wire 26 with the post G² of the switch G.

One end of the bottom oven heating section

D¹ connects through a lead 27 with the lead 19 which connects with a negative source of current supply, while the other end of the section D¹ connects through a lead 28 with the other bottom oven heater section D². The wire 28 in turn connects through a lead 29 with the post H⁴ of the switch H. The other end of the heater section D² connects through a lead 30 with the post H² of the switch H. The post G¹ of the switch G is connected through a lead 31 with a post F²³ of the switch F.

The operation of this wiring system is as follows: In general it will be remembered that with the switches G and H turned to an "off" position, the switch E will control the top oven heating elements A¹ and A² alone. Each switch is provided with means to be turned to "off" position, "full" position in which its heating elements are given the maximum wattage, "medium" position in which they are supplied with one-half the power of the "full" position, and a "low" position in which the heating elements are supplied with one-fourth the wattage of the "full position". For convenience, the actual wattage furnished to each heating element is noted on that element in each of the wiring diagrams (Figs. 1 to 4).

In Fig. 1 all the switches are turned to "full" position. Current from the positive lead 16 enters the switch E on the post E³ and passes through the rotatable contact E¹⁵ to the post E⁴, and thence through the lead 22 to the heating elements A¹ and A². Current then passes through the heating element A¹ to the lead 19 and thence back to the negative supply main. Current from the lead 22 also passes through the heating section A² and back through the lead 17 to the post E² of the switch, thence through the rotatable contact E⁹ and to the post E¹ and thence to the lead 20 to the negative supply main.

It will be seen that when the switch E is turned to the "full" position, the top oven sections A¹ and A² are supplied with the maximum of power, namely, 500 watts each, even though the switches G and H are also turned to their "full" position. This is true of the top oven heating units A¹ and A² which will be given the maximum amount of current when the switch E is turned to the "full" position no matter what position the switches G and H may assume.

Continuing with the wiring diagram of Fig. 1, it will be seen that no current will flow through either of the top oven sections C¹ or C². The maximum of power of 250 watts will flow through the section D¹ of the bottom oven heater unit. This is due to the fact that the rotatable switch element H¹⁵ connects the post H³ to the post H⁴ of the switch H, and this in turn passes current through the lead 29 to the heater section D¹ and thus direct to the negative terminal connection 19. By following up the other leads, it will be seen that they will return upon themselves in such a way as to prevent current passing therethrough from the positive to the negative terminals.

Referring now to Fig. 2, the parts are in the position shown in Fig. 1 except that the switch E, F is turned from the "full" position to the "medium" position. By so doing, the heater section A¹ is supplied with current substantially as before, while the heater section A² is caused to double back upon the positive lead through the contact member E¹⁵ of the switch E. No current, therefore, flows.

It will now be observed that current flows

through the heater section D^2 , this current flowing through the leads 30, H⁹, 25, F²², F¹⁵, F²⁴ and 21, and 19 back to the negative supply main. At the same time current is caused to flow through the heating unit C¹, the return being through the leads 25, F²², F¹⁵, 21 and 19 back to the negative source of current. It will be seen that in Fig. 1 1250 watts only are obtained, 500 watts flowing through each of the units A¹ and A², and 250 watts flowing through the bottom oven unit D¹. In the setting shown in Fig. 2, 1250 watts flow, and this is divided as follows: 500 watts through the top oven section A¹, 250 watts through the top oven heater unit C¹, and 250 watts each through the bottom oven heating units D¹ and D². Thus the heating units D¹ and D² are supplied with a maximum of current in the setting shown in Fig. 2, and not in Fig. 1. This change is brought about by movement of the switch E, F without any change whatever in the switches G and H which primarily control these units.

Referring now to Fig. 3, the switch E, F is turned to the "low" position. In this case, current from the positive lead 16 flows to the post E⁹, thus flowing through the contact E¹⁵ to the post E², thence to the lead 17, and then through the heating units A² and A¹ in series, and thence back to the lead 19 to the negative source of supply. Thus only 125 watts flows through each of the heating units A¹ and A². At the same time it will be observed that the heater unit of C² previously unheated now receives current. This is due to the fact that current will now flow through the leads 26, G², G⁹, G¹, 31, F²³, F¹⁵, F²⁴, 21, and 19, back to the negative source of supply.

In Fig. 4, the switch E, F is turned to the "off" position and no current flows through the top oven heating sections A¹ and A². It will also be observed that in Fig. 3, 1250 watts are all that can be obtained, the switches G and H still remaining at the "full" position, and the heater units C¹, C², D¹, and D² getting their maximum of 250 watts each, while the heater units A¹ and A² each receive 125 watts.

With the switches as shown in Figs. 3 and 4, the amount of power supplied to the units C¹, C², and D¹, D² may be correspondingly reduced by manipulation of the switches G or H. It is not necessary, however, that all of the possible positions and combinations of parts of these switches be shown. To do so, would needlessly expand this application and make it much more difficult to read rather than otherwise. It will be understood, however, that in addition to each pair of heating elements C¹ and C² being heated at a rate of 250 watts, either singly or in combination, they can also be placed in series as was done with the heating units A¹ and A² of Fig. 3, by turning the corresponding controlling switch to the "low" position. Thus the top oven heater may use both of the heating units in parallelism, thereby using 500 watts. Either of these sections may be used alone, thereby using 250 watts, or they may be in series, thereby using 125 watts. The switch G controls the top heating elements C¹, C², independent of the other switches so long as the top oven heating units A¹ and A² are not supplied with more than 125 watts each, as shown in Fig. 3. It will be seen that I have provided an oven with two heating units and an outside cooking unit, each of which may be separately controlled by its individual switch, (so long as the total load is not exceeded) and the whole so wired that only a predetermined maximum of power is permitted to flow at any one time, namely, 1250 watts, al-

though the sum total of available heating units is 2000 watts. This enables me to place the oven on the usual lamp cord which can be supplied from any wall socket and still bring it within the requirements of the release of the Insurance Underwriters. 80

While I have shown and described but a single embodiment of my invention, it is to be understood that it is capable of many modifications. Changes, therefore, in the construction and arrangement may be made which do not depart from the spirit and scope of the invention as covered by the appended claims. 85

I claim:

1. In combination, three electric heating units each comprising a plurality of heating elements, and means comprising three electrically interconnected switches for connecting heating elements of said units in series and in parallel one of said switches having connections to control the various units for any position of the other switches so as to prevent the sum total of power consumed by said units from exceeding a predetermined maximum, each of said switches controlling a different one of said units when the total power does not reach said maximum. 90

2. In combination, three electric heating units one of which is of a different capacity from the others, each comprising a plurality of heating elements, and means comprising electrically interconnected switches for connecting heating elements of said units in series and in parallel one of said switches having connections to control the various units for any position of the other switches so as to prevent the sum total of power consumed by said units from exceeding a predetermined maximum, each of said switches controlling a different one of said units when the total power does not reach said maximum. 105

3. In combination, three electric heating units one of which is of a different capacity from the others, each comprising a plurality of heating elements, and means comprising electrically interconnected switches for connecting heating ele- 110

ments of said units in series and in parallel and for modifying the connections to one of the units for a certain position of said switches so as to prevent the sum total of power consumed by said units from exceeding a predetermined maximum 115 less than the total capacity of the units, each unit being normally controlled by one of said switches when the total power consumed by the units does not reach said maximum, said maximum being the same for all combinations of 120 settings of said units.

4. In combination, three electric heating units one of which is of substantially twice the capacity of the others, each comprising a plurality of heating elements, and means comprising electrically interconnected switches for connecting heating elements of said units in series and in parallel and for modifying the connections to one of the units for certain positions of said switches so as to prevent the sum total of power consumed by said units from exceeding a predetermined maximum less than the total capacity of the units, each unit being normally controlled by one of said switches when the total power consumed by the units does not reach said maximum, said maximum being the same for all combinations of settings of said units. 135

5. In combination, three electric heating units one of which is of a different capacity from the others, each comprising a plurality of heating ele- 140

ments, and means comprising three electrically interconnected switches for connecting heating ele- 145

ments of said units in series and in parallel and for modifying the connections to one of the units for certain positions of said switches so as to prevent the sum total of power consumed by said units from exceeding a predetermined maximum less than the total capacity of the units, each unit being normally controlled by one of said switches when the total power consumed by the units does not reach said maximum, said maximum being the same for all combinations of settings of said units. 150

- 5   ments, and means comprising electrically inter-connected switches for connecting heating elements of said units in series and in parallel and for modifying the connections to one of the units for certain positions of said switches so as to prevent the sum total of power consumed by said units from exceeding a predetermined maximum less than the total capacity of said units, each unit being normally controlled by one of said 10 switches when the total power consumed by the units does not reach said maximum, one of said units getting its normal amount of power corresponding to the setting of its switch irrespective of the settings of the other switches.
- 15   6. In combination, three electric heating units one of which is of substantially twice the capacity of the others, each comprising a plurality of heating elements, and means comprising electrically interconnected switches for connecting heating elements of said units in series and in parallel 20 and for modifying the connections to one of the units for certain positions of said switches so as to prevent the sum total of power consumed by said units from exceeding a predetermined maximum less than the total capacity of said units, each unit being normally controlled by one 25 of said switches when the total power consumed by the units does not reach said maximum, said maximum being the same for all combinations of 30 settings of said units, the larger of said units getting its normal amount of power correspond-

ing to the setting of its switch irrespective of the settings of the other switches.

7. In combination, three electric heating units each comprising a plurality of heating elements, and means comprising three electrically interconnected switches for connecting heating elements of said units in series and in parallel and for modifying the connections to one of the units for a certain position of said switches so as to prevent the sum total of power consumed by said units from exceeding a predetermined maximum, each of said switches controlling a different one of said units when the total power does not reach said maximum, said total being less than the sum of the maximum power draw of all the units.

8. In an electrical heating system in combination, three heating units each having two heating elements, one of said units having a capacity of substantially double that of each other unit, a switch for each unit having connections for controlling its corresponding heating elements, the switch for the larger capacity unit being interconnected with the elements of the other units whereby when said larger capacity unit is connected for any heating capacity the circuits of the other units will be modified to limit the total consumption not to exceed a maximum amount less than the total capacity of the several units.
